UNITED STATES PATENT OFFICE.

JOSEPH PIENOVY, OF NEWARK, NEW JERSEY.

DESIGN FOR INDIA-RUBBER OVERSHOES.

Specification forming part of Design No. 11,400, dated September 9, 1879; application filed August 12, 1879.
[Term of patent 7 years.]

To all whom it may concern:

Be it known that I, JOSEPH PIENOVY, of Newark, New Jersey, have originated and designed a new Pattern for or Style of India-Rubber Overshoes, of which the following is a full, clear, and exact description, reference being had to the accompanying drawing, making part of this specification.

The general design or form of the shoe, subject-matter of this patent, suggests the style worn in the time of Louis XIV.

In my new style of rubber shoe the contour-line of the upper is indicated in the drawing by the line *a*, *b*, *c*, and *d*, being curved to form a tongue, resting upon the instep. This line is shown on the shoe by imitation stitching from *a* to *b* on the one side and from *a* to *b'* on the other, and then to suggest its shape and continuance under the side laps by a ridge or depression from *b* to *c* and *d* on the one side, and similarly on the opposite side. The contour-line of the counter, rear, or heel portion of the shoe is also indicated by an imitation-stitching line extending from the highest point

in the portion above the heel at *e* on both sides symmetrically to *b*, *g*, *h*, *i*, and *k*. From *e* to *b* and *b'* the stitching-line runs parallel with the upper edge of the shoe, and from *b* to *g*, *h*, and *i* a false edge is formed upon the rubber parallel and in close proximity to the stitching-line. A short line of imitation stitching from *i* to *m* is to suggest a seam whereby the lap is secured to the upper.

At the line of juncture of the laps a bow or buckle may be placed for extra ornament.

What I claim is—

The herein-described design of a rubber shoe, having a counter and tucks or flaps on the vamp, indicated by imitation stitching on the surface of the upper, the contour-line of which upper is indicated by lines in relief, *a*, *b*, *c*, and *d*, as set forth.

In testimony whereof I have hereunto signed my name this 11th day of August, A. D. 1879.

JOSEPH PIENOVY.
